UNITED STATES PATENT OFFICE

1,997,934

STEAM GENERATOR

John Johnson, Cheam, England

Application July 10, 1933, Serial No. 679,787

4 Claims. (Cl. 122—480)

As is well recognized, certain services necessitate the use of different qualities of steam, either at different times or concurrently, to meet which separate boilers are most commonly used. This is so, for instance, on board ship where donkey boilers usually operate auxiliaries such as deck machinery, galley services etc. leaving the main boilers for propulsion. Space is at all times a consideration and, coupled with weight, is especially so on a ship. The object of the present invention is to provide a steam generator having a much greater range of usefulness than has hitherto been devised and one which has a very high efficiency as well as other attributes making it particularly applicable for marine work.

To this end advantageously a boiler is employed of the type wherein the gases from furnaces passing through the back plate of a cylindrical shell are, on their way to return smoke tubes, received in a combustion chamber containing tubes designed to assist water circulation in the boiler, and a superheating system likewise situated in said combustion chamber, the invention consisting in combining with the superheater a desuperheater and selective delivery valve means therefor, allocating the superheating system to some fraction of the whole return smoke tube system, arranging the water circulating tubes which bound the combustion chamber so that some of the gases from the furnaces can travel between and past them first in one direction and then in the opposite direction, providing the exit ends of the furnaces with baffles to assist the flow of gases past the water circulating tubes and providing the exit ends of the respective nests of tubes of the smoke tube system with dampers whereby the conditions of gas flow in relation to the superheating system can be widely varied to suit requirements. Finally the whole boiler is preferably enclosed in a casing which constitutes an air jacket to conserve heat and increase the overall efficiency.

Such a boiler will be found to meet all the important demands of modern practice. Thus, in addition to the inherent advantage of the boiler proper, which includes a water capacity large yet not unduly large as is demanded with an internal combustion chamber, it is possible to economically supply saturated or lightly superheated steam alone such as may be required for the operation of auxiliaries while a vessel is in port; to supply steam for main engine use alone with varying degrees of superheat; or to utilize steam of these different characters simultaneously for both such purposes.

The accompanying drawings illustrate an equipment according to the invention, Fig. 1 being a sectional side elevation of the boiler. Fig. 2 is a front view, the left hand half of which corresponds to a section on the line 2—2 of Fig. 1 and the right hand half to an elevation with parts removed. Fig. 3 is a sectional plan view corresponding to Fig. 2 and Fig. 4 is a sectional plan view corresponding to part of Fig. 1. Fig. 5 is a front view of the boiler with parts removed.

As here shown, 1 represents the boiler shell, 2 its internal furnaces, 3, 4 and 5 the associated nests of return smoke tubes, 6 the refractory lining of the external combustion chamber, 7 the tubular portion of a superheater arranged in the combustion chamber at the entrance end of the nest 4 of smoke tubes and connecting the external saturated steam header 8 to the external superheated steam header 9. 10 are gilled desuperheating pipes located in the boiler, 11 is an auxiliary steam stop valve adapted to admit steam to the desuperheater and 12 is a superheated main steam stop valve. 13 are the water circulating tubes which are arranged at a distance from the rear wall 6 such that gases from the furnaces 2 can follow the paths indicated by the arrows in Fig. 1. This gas flow is assisted by baffles 14 secured to the back plate 15 of the boiler which baffles act to constrict the path somewhat and increase the velocity of flow towards and across the tubes 13. The smoke box 16 is divided by walls 17 into three compartments corresponding to the tube nests 3, 4 and 5 and each is adapted to be independently placed in communication with the uptake 18 by appropriate manipulation of dampers 19. One wall 18a of this uptake is separated from the front plate 20 of the boiler by an air space formed in part by an insulating envelope 21 which surrounds the whole of the remainder of the boiler except the side walls (6) of the combustion chamber where access doors 22 are provided. 23 represents the hot gas inlet to an air heater (not shown) which delivers into the boiler air jacket at 24.

The arrangement is such that assuming a supply of steam primarily, for say, propulsion only is required, then valve 12 will be opened and valve 11 closed. The degree of superheat at this time can be variously adjusted. For example normally under full load all three furnaces 2 will be in use and all three dampers 19 opened. If one or other or both of the wing dampers 19 be closed, more gases may be caused to flow through the central nest 4 of tubes and influence the superheater 7, thereby increasing the degree of super-

heat. On the other hand if the central damper 19 be closed or partially closed and the others or one of the others alone left open the effect of the superheater 7 can be reduced until it may 5 be regarded as negligible. Thus in port for example, saturated steam may be supplied to auxiliaries through the valve 12 and other distributing valves.

If, while superheated steam is being used as 10 supplied through valve 12, it should be desired to supply saturated steam to auxiliaries, this can be done by opening valve 11 also.

What I claim is:—

1. In a steam generating plant, a boiler of the 15 Scotch type having a plurality of furnaces, correlated nests of smoke tubes and an external combustion chamber connecting the furnaces with the smoke tube nests and containing water 20 circulating tubes disposed so that gases from the furnaces can travel past and between them in opposite directions, a superheater located within said combustion chamber above the furnaces opposite the smoke tube nest of one of the same in the path of combustion gas flow, means at 25 the back ends of the several furnaces for directing the gases past and between the circulating tubes as aforesaid and past the superheater, and dampers at the front end of each of the smoke tube nests whereby the flow of gases in relation 30 to the superheater can be controlled therethrough for varying the degree of superheating.

2. A steam generating plant, comprising in 35 combination, a multi-furnace boiler having correlated nests of smoke tubes and an external combustion chamber connecting the furnaces with the smoke tube nests and containing water 40 circulating tubes disposed so that gases from the several furnaces can travel past and between them in opposite directions, a superheater located within said combustion chamber above one of

the furnaces opposite the smoke tube nest thereof in a position to be contacted by the combustion gases, and a damper at the front end of the nests of tubes arranged to vary the proportion of the gases passed through the various nests of smoke tubes whereby the proportion of the gases passed over the superheater may be varied.

3. A steam generating plant, comprising in combination with a multi-furnace boiler having corresponding nests of smoke tubes and a combustion chamber connecting the furnaces with the smoke tube nests and containing water circulating tubes disposed so as to permit the gases from the furnaces to travel past and between them in different directions, a superheater located within said combustion chamber above one of the furnaces opposite the nest of smoke tubes therefor in a position to be contacted by the flowing combustion gases, and a damper at the front end of one of the nests of smoke tubes arranged to vary the proportion of the gases passed through the various nests of smoke tubes whereby the proportion of the gases passed against the superheater may be varied.

4. A steam generating plant, comprising a 25 boiler having a central and two wing furnaces, a nest of smoke tubes associated with each of said furnaces, an external combustion chamber connecting the furnaces with the smoke tubes, a superheater located within said combustion 30 chamber in the path of the combustion gas flowage above the central furnace directly opposite the nest of smoke tubes associated therewith, and a damper at the front end of the several smoke tube nests; said damper being arranged to vary 35 the proportion of the gases passed through the various nests of smoke tubes whereby the proportion of the gases passed in contact with the superheater may be varied.

JOHN JOHNSON. 40
